(57) **CLAIM**

The ornamental design for a "stringed musical instrument," as shown and described.

DESCRIPTION

FIG. 1 is a front perspective view of a stringed musical instrument which embodies my new design;

FIG. 2 is a front elevational view thereof;

FIG. 3 is a sectional view taken at line 3 in FIG. 2;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

In FIGS. 1-3, the broken lines represent the portions of the stringed musical instrument that form no part of the claimed design.
